[57] **CLAIM**

The ornamental design for a dispenser for powdery, paste-like, semi-fluid, or fluid products, such as sweeteners, as shown and described.

DESCRIPTION

FIG. 1 is a front elevational view of a dispenser for powdery, paste-like, semi-fluid, or fluid products, such as sweeteners showing my new design;

FIG. 2 is an end view of the top thereof;

FIG. 3 is an end view of the bottom thereof;

FIG. 4 is a left side view thereof;

FIG. 5 is a right side view thereof;

FIG. 6 is a rear elevational view thereof; and

FIG. 7 is a perspective view thereof.

The characteristic feature of my design resides in the appearance of a fire-lighter.
